UNITED STATES PATENT OFFICE.

RUFUS F. HERRICK, OF WINCHESTER, MASSACHUSETTS.

RUBBER-COMPOUND PAVING BLOCK.

Application filed September 16, 1924. Serial No. 738,018.

This invention relates to an improved rubber compound paving block, or slab for roadways, and further the invention relates to an improved roadway of which the said blocks constitute the uppermost surface, the same being an improvement upon the invention disclosed by me in my application Serial No. 688,297, filed January 24, 1924 entitled "Roadway with surface of rubber 10 pound".

The object of the invention is to provide a paving block of rubber compound which may be readily and cheaply manufactured, and which may be quickly and practically laid to constitute the uppermost surface of a roadway, such a roadway being practically noiseless when vehicles pass thereover and extremely comfortable for the occupants of said vehicles, the upper rubber compound 20 surface being yielding, and further the blocks would be much lighter than granite and would impart less vibration when used on bridges.

The rubber compound of which my improved paving blocks are constructed may contain fibrous material and may be constructed from old rubber and fabric automobile tires. The paving block constituting this invention is made of suitable thickness 25 and size, preferably of rectangular outline and about an inch and a half thick, and upon the under side of the completed paving block a plurality of anchoring projections integral with the paving block are provided which extend preferably longitudinally of the block and transversely of the roadway in which they are incorporated.

These anchoring projections are preferably tapered, the opposite faces thereof 40 converging downwardly from the under face of the paving block so that the blocks may be readily moulded and also readily inserted in a layer of temporarily plastic material, such as sand cement mortar, and when the 45 sand cement mortar has hardened, the paving blocks will be firmly imbedded therein and will cohere thereto.

It is evident, however, that the anchoring projections may have the opposite faces 50 thereof parallel without departing from the spirit of my invention, the preferred form of the projections being tapered, however, as this form is more practical from the moulding standpoint, and also for the laying of 55 the block on the surface of the temporarily plastic material, the tapered projections be-

ing more easily and practically forced into the temporarily plastic material.

The paving block of this invention may be moulded with a roughened under surface 60 and the projections thereon may also have roughened surfaces.

The invention consists in the improved paving block for roadways and in a roadway of which said paving blocks form the upper- 65 most layer, all as hereinafter set forth in the specification and particularly as pointed out in the claim.

Referring to the drawings:

Figure 1 is an underneath plan view of a 70 paving block embodying my invention.

Fig. 2 is a side elevation of the paving block.

Fig. 3 is an enlarged section taken on line 3-3 of Fig. 1 with the block in its normal 75 position.

Fig. 4 is a sectional detail illustrating a portion of a roadway with the paving block 80 of my invention incorporated therein.

Fig. 5 is an end elevation of my improved 85 paving blocks, the anchoring projections being shown with their opposite faces parallel.

Like numerals refer to like parts throughout the several views of the drawings.

In the drawings, referring to Figs. 1 to 85 4 inclusive, 5 is a paving block of rubber compound which consists of a body portion 6 with ribs 7 extending longitudinally along one surface thereof. When the blocks are laid, however, to form the upper surface of 90 a roadway, the ribs 7 extend transversely of the roadway.

The blocks are of rubber compound, but may have a mineral aggregate consisting of sand or stone chips incorporated therein, or 95 may be constructed with fibrous material therein so that old discarded automobile tires may be used for the purpose.

The opposite faces 7' of the projections or ribs 7 converge downwardly, thus making 100 it practical and easy to mould the blocks of rubber compound. The ribs 7 are arranged in series, preferably parallel to each other and spaced apart, both longitudinally and transversely of the block, thus leaving spaces 105 8 and 9 therebetween, and also the outer ends of the ribs are spaced apart from the ends of the block so as to provide spaces 10 between the outer ends of the ribs and the adjacent 110 ends of the block, the object of this arrangement and construction being to permit the temporarily plastic material, such as sand

cement mortar into which the ribs project in the completed roadway, to enter these spaces 8, 9 and 10 and thus lock the paving block against movement either longitudinally or transversely thereof, and this feature of the construction of the paving block of this application constitutes the principal difference between it and the paving blocks disclosed in my aforesaid application.

10 In order to more securely anchor the paving blocks in the layer of temporarily plastic material, rods or wires 11 are provided which project through the anchoring projections 7 and are spaced apart from the 15 under face of the body portion 6 of the block. These rods preferably project at their opposite ends beyond the anchoring projections so as to still more securely anchor the block to the layer of temporarily plastic 20 material.

In Figure 5 a modified form of the paving block of this invention is illustrated which is like the paving block illustrated in Figs. 1 to 4 inclusive, except that the anchoring 25 projections 12 have parallel faces 13 instead of being tapered. The body portion 6 is the same as in the form of my invention illustrated in Figs. 1 to 4 inclusive, and the anchoring rods 11 are the same and are attached to the projections in the same manner.

The roadway is constructed by first constructing a layer of macadam, or other suitable material 14, then upon this layer which 35 constitutes the base is superimposed a layer of sand cement mortar 15, which constitutes a cushion, and while the sand cement mortar is soft or temporarily plastic, and before it sets, the uppermost layer 16 of the roadway 40 is laid thereon, this layer consisting of a plurality of paving blocks of the construction hereinbefore set forth, the paving blocks being forced into the layer 15 of sand cement mortar while the same is plastic or 45 soft, preferably by means of a light steam road roller.

The paving blocks having been laid as set forth with the ribs 7 projecting downwardly therefrom into the layer of sand cement 50 mortar 15, the sand cement mortar will then set and securely lock the upper layer 16 to

the sand cement mortar layer 15, and the sand cement mortar layer 15 will be firmly positioned upon and locked to the macadam or base 14 of the roadway by the sand cement mortar projecting into said base and setting therein. The joints between adjacent blocks may be filled with sand, hot bitumen or rubber compound.

For bridge construction on an ordinary 60 roadway surface thereof, however, the layer 15 preferably consists of Portland cement mortar, and the base may be of any suitable material.

While the material of which the paving 65 block is composed has been hereinbefore set forth as of rubber compound, it is evident that without departing from the spirit of this invention any material which can be moulded into the form of a paving block 70 with anchoring projections thereon would be the equivalent of rubber, so far as this invention is concerned, and it is to be understood that I do not confine my invention to a paving block of rubber compound, but 75 although rubber is the preferred form, the paving block may be composed of other compounds such, for example, as asphalt or bituminous compounds.

It will also be understood that the article 80 of this invention is not confined specifically to a paving block for streets, but may be used with modifications as to thickness, etc. for what is known as industrial tiles.

I claim:—

A paving block for roadways constructed in one piece of rubber compound and comprising a body portion having a flat bottom face and a series of ribs extending longitudinally thereof and projecting downwardly therefrom, the opposite side faces of said ribs converging downwardly and said ribs being spaced apart both transversely and longitudinally of said block and from the opposite sides and ends thereof, the spaces between said ribs being open at their opposite ends, and rods projecting through said ribs and spaced apart from the flat bottom face of said block.

In testimony whereof I have hereunto set 100 my hand.

RUFUS F. HERRICK.
